UNITED STATES PATENT OFFICE

SOLOMON M. SAGER, OF GLENCOE, ILLINOIS

SWIVEL JOINT

Application filed April 1, 1931. Serial No. 526,805.

The present invention relates to an improved type of a universal swivel joint for use in mounting a pen receiving socket upon a block or base forming a part of a fountain pen desk set.

It is an object of this invention to provide an improved simplified form of a swivel joint in the form of a barrel-shaped unit having a resilient connection with a supporting member and furthermore being constructed to support a pen receiving socket to permit the socket to be universally adjusted.

It is also an object of this invention to provide a fountain pen socket support in the form of a sectional barrel unit, the middle portion of which affords a pivotal support for the socket while the end portions of the barrel unit are supported on a rotatably mounted supporting fork which is spring controlled and which is engaged on a clamping unit adapted to be rigidly secured to the base member of a fountain pen desk set.

It is a further object of this invention to provide a swivel joint comprising a clamping unit and a barrel unit connected with one another by means of a spring controlled stem unit, said barrel unit being of sectional form with one of the sections affording a support for a fountain pen socket, the pivotal movement of which is adapted to be controlled by the adjustment of the end sections of the barrel unit with respect to one another.

It is furthermore an object of this invention to provide an improved type of fountain pen desk set having an improved swivel joint including a spring controlled rotatable member supported in a sectional clamping unit and supporting interfitting adjustable members on one of which an intermediate member is rotatably supported for carrying a fountain pen receiving socket to permit the socket to be universally adjusted.

Another object of the invention is to provide a universal joint for the socket of a pen desk set, said joint embracing interfitting supporting members adapted to be clamped in position projecting through a supporting base and having rotatably engaged therein a spring controlled fork member on which a plurality of interfitting swivel joint mem-

bers are adapted to be supported to support and control the operation of a pen socket.

It is an important object of this invention to provide an improved type of swivel joint for use in connection with a pen desk set 55 whereby a fountain pen socket is adapted to be mounted on a supporting base or block by means of an improved swivel joint unit permitting the socket to be adjusted with a universal movement, said swivel joint unit 60 embracing interfitting clamping members on one of which a spring controlled supporting fork is rotatably mounted to afford a support for an adjustable knuckle, including a plurality of interfitting adjustable parts 65 adapted to be conveniently set with respect to one another to govern the ease with which the pivotal adjustment of the pen receiving socket is adapted to be moved.

Other and further important objects of 70 this invention will be apparent from the disclosures in the specification and the accompanying drawings.

The invention (in a preferred form) is 75 illustrated in the drawings and hereinafter more fully described.

On the drawings:

Figure 1 is a front elevational view of a pen desk set including an improved swivel joint embodying the principles of this invention.

Figure 2 is a side elevation of the desk set illustrating a fragmentary portion of a pen inserted in the desk set socket.

Figure 3 is an enlarged fragmentary detailed section taken on line III—III of Figure 2 with parts shown in elevation.

Figure 4 is a detailed transverse sectional view taken on line IV—IV of Figure 3.

Figure 5 is an enlarged inner end view of 80 the washer member forming a part of the swivel joint.

As shown on the drawings:

The reference numeral 1 indicates a base plate or block forming a part of a fountain pen desk set with said base plate provided with a passage or opening extending through the base plate from top to bottom and designated by the reference numeral 2. The lower end of the passage or opening 2 at its 100

lower end is enlarged to form a groove or recess 3. The opening in the base member 1 is provided for the reception of a clamping or supporting unit comprising an internally threaded sleeve 4 having a peripheral flange 5 integrally formed on the lower exterior portion thereof. Projecting downwardly into the passage 2 and adjustably threaded into the internally threaded sleeve 4 is an 10 externally threaded hollow sleeve or shank 6 which is integrally formed on the under side of a clamping head or plate 7. The externally threaded shank 6 and the clamping plate 7 form a clamping bushing which is adapted to be tightly threaded into the base sleeve 4 and against the top surface of the base member 1 to provide a rigid support for the swivel joint mechanism.

Projecting downwardly through a central 20 opening in the clamping plate 7 of the bushing member is a post or stem 8 having a collar 9 integrally formed on the upper portion thereof and adapted to rest on the plate 7. The stem 8 is rotatably engaged in the bushing plate or head 7 and has a coiled spring 10 engaged around the body portion thereof with the upper convolution of the spring contacting the inner surface of the head 7. The lower end of the control spring 10 seats 30 upon a washer or ring 11 which is engaged around the stem and is supported by means of a pin 12 which projects diametrically through the stem. The spring 10 acts to resiliently hold the collar 9 of the stem in contact with the head or top plate 7 of the bushing member of the base unit of the swivel joint. Integrally formed on the collar 9 is a supporting fork or U-shaped bracket comprising a cross-piece or base member 13 40 having integrally formed on the ends thereof parallel arms 14. Each of the arms 14 has the upper end thereof terminating in an apertured disc or ring 15. The apertured arms of the supporting fork are provided for the purpose of receiving and supporting a sectional swivel unit or knuckle in its completed form having the shape of a barrel. The adjustable swivel unit or knuckle comprises an intermediate member or middle section 50 comprising an axially passaged body section 16 having an internally threaded radial recess or pocket 17 formed in the outer peripheral surface thereof for removably receiving a threaded stud 18. The threaded stud 18 is integrally formed on the lower end of a metal base 19 of a fountain pen or scribing instrument receiving socket 20 provided with a suitable receiving pocket for the removable reception of a writing pen 21 or the like.

The socket 20 may be constructed of hard rubber, bakelite or any other suitable material or, if preferred, the socket may be constructed of metal, in which case the base 19 may be integral with the body portion of 60 the socket.

The body portion of the barrel shaped swivel joint is adapted to be positioned between the apertured disc 15 of the rotatable fork member and is rotatably supported on a hollow shaft or stem 22 which is integrally formed axially on the inner end of a barrel head 23, the inner end of which is provided with a round recess 24 and with a notch 25 as clearly illustrated in Figure 4 to permit the barrel head to engage over and enclose one of the apertured discs 15 and one of the arms 14 of the rotatable fork member. When the internally threaded sleeve 22 projects through the opening of the two discs 15 of the fork member the barrel head 23 is adapted to engage over one of the discs 15 with the arm portion of said disc engaged in the notch 25 thereby holding the barrel head 23 against rotation with respect to the forked member.

Removably engaged on the projecting end of the internally threaded shaft 22 to the outside of the second apertured disc 15 of the forked member is a barrel washer section 26 having a middle opening 27 to engage over the hollow shaft 22 and also provided on its inner side with a circular recess or opening 28 and a notch 29 as clearly illustrated in Figure 5. The barrel washer section 26 is thus adapted to be engaged on the hollow shaft 22 to seat over the second disc 15 and its arm 14 to hold the washer section against rotation with respect to the forked member.

The barrel head 23 and the barrel washer section 26 when in position contact the end surfaces of the middle section or body portion 16 of the barrel shaped swivel unit. For the purpose of holding the barrel head 23 and the barrel washer section 26 clamped or frictionally engaged against the outer or end surfaces of the barrel middle section 16 an adjustable barrel head or end barrel section 30 is engaged to the outside of the washer section 26 by means of a screw stem 31 which is integrally formed axially on the inner side of the end barrel section or head 30, as clearly illustrated in Figure 3.

The threaded stem or screw 31 is adapted to be threaded into the internally threaded sleeve or shaft 22 of the barrel head section 23 thereby clamping or securing the various barrel sections in contact with one another to complete the swivel barrel shaped joint and hold the middle section 16 of the barrel on which the end socket is supported in frictional engagement between the disc members 15 of the fork unit. By adjusting the screw stem 31 of the barrel head 30 with respect to the internally threaded shaft 22 of the barrel head 23 the arm portions of the rotatable forked unit are adjustably compressed or released with respect to the side surfaces of the middle section 16 of the barrel unit to either tighten or loosen the same to permit the pen receiving socket together with the

middle barrel section 16 to be pivotally adjusted into different positions.

It will thus be noted that an improved swivel joint has been devised wherein the joint unit takes the form of a barrel and permits the pen receiving socket to be pivotally adjusted on the hollow shaft 22 of the barrel unit while the barrel unit together with the socket supported thereon is adapted to be rotatably mounted with respect to the clamping section 7 by simply rotating the stem 8 of the forked unit with respect to the base top section 7. The arrangement affords a universal joint for the pen socket wherein the rotatable parts are adapted to be moved with respect to one another and wherein the rotatable fork portion is adapted to be rotated with respect to the base section 7 so that there is no wear on the material forming the base block 1 of the fountain pen desk set.

The spring controlled fork unit on which the barrel shaped swivel joint is supported is permitted to have slideable movement with the base members 7 and 4 with the spring 10 serving to resiliently hold the collar 9 of the fork unit in contact with the top surface of the cap or top unit 7 of the base section.

The barrel unit on which the pen receiving socket 20 is supported is arranged so that the middle section of the barrel is adapted to be rotated on the hollow shaft 22 to permit the socket to be pivotally swung with respect to the fountain pen desk set block or base section 1 while the entire barrel unit together with the socket is adapted to be rotated with the fork unit which is pivotally supported on the clamping member 7 forming a part of the base portion of the socket supporting unit. It will thus be noted that an improved swivel point device has been provided permitting universal movement of the pen supporting socket and obviating wear of the base block 1 since the arrangement is such that there are no moving parts coming in contact with the base block or base section 1.

It will of course be understood that various details of construction may be varied through a wide range without departing from the principles of this invention, and it is therefore not the purpose to limit the patent granted hereon otherwise than necessitated by the scope of the appended claims.

I claim as my invention:

55 1. A pen desk set comprising a base member, interfitting supporting members projecting through said base member and clamped thereto, a spring controlled fork unit rotatably mounted on one of said supporting members, a swivel unit adjustably supported on said forked unit, and a pen supporting socket supported on said swivel unit.

60 2. A pen supporting desk set comprising a base plate, interfitting supporting members projecting through said base plate and

clamped thereto, a spring controlled forked unit rotatably supported on one of said supporting members, interfitting joint members supported on said forked unit, a swivel member rotatably supported on said interfitting joint members and controlled by the adjustment of said interfitting joint members, and a pen supporting socket removably engaged with said swivel member. 70

3. A pen supporting device comprising a base section, a spring controlled forked unit rotatably supported thereon, an adjustable barrel shaped swivel unit supported on said forked unit, and a pen supporting socket supported on said barrel shaped swivel unit. 75

4. A pen supporting device comprising a supporting unit, a fork member rotatably supported therein, interfitting members carried by said fork member, a swivel member rotatably supported on one of said interfitting members between the arms of said fork member, and a pen receiving socket removably secured to said swivel member. 80

5. A pen supporting device comprising a base, a fork rotatably supported on said base, interfitting control members supported on said fork and interfitting the same, a swivel member rotatably supported on said interfitting control members, said control members adjustable with respect to one another 90 to cause the fork member to frictionally engage the swivel member to control the rotation thereof, and a pen socket removably engaged on said swivel member. 95

6. A pen supporting device comprising a base member, a fork member rotatably supported therein, means for adjusting the arms of said fork member, a swivel member rotatably supported on said means and controlled by the adjustment of the arms of said fork 100 member, and a pen supporting socket carried by said swivel member and having universal movement with respect to said base member. 105

7. A pen supporting device comprising a base section, a fork member rotatably supported thereon, an adjustable barrel shaped knuckle unit supported on said forked unit, and a pen receiving socket removably engaged on said adjustable barrel shaped knuckle unit. 110

8. A pen supporting device comprising a support, a stem rotatably mounted therein, spaced apertured parallel arms formed on said stem, an internally threaded hollow shaft projecting through said arms, a ring member rotatably mounted on said shaft between said arms, a pen carrying socket supported on said ring member, a notched head integrally formed on one end of said shaft and interfitting one of said arms to hold the 120 shaft against rotation, a notched washer engaged on said shaft and interfitting the other of said arms to hold the washer against rotation, and a headed screw member adjustably engaged in said shaft and adapted to be ad- 125 130

justed to frictionally adjust said arms with respect to said ring member to control the rotational movement thereof.

9. A pen supporting device comprising a 5 rotatable forked member, a shaft supported thereby, a ring member rotatably supported on said shaft between the arms of the forked member, a pen carrying socket removably engaged on said ring member and movable therewith, and means adjustably engaged 10 with said shaft for adjusting the arms of the fork member to control the rotational movement of said ring member.

10. A pen supporting device comprising 15 a base, a fork member rotatably supported therein and including a pair of spaced apertured arms, a shaft member supported by said arms, a socket member rotatably supported on said shaft between said arms, and 20 means for adjusting said arms to control the rotational movement of said socket member.

11. A pen supporting device comprising a 25 base means, a stem rotatably supported therein, means for resiliently holding the stem in position, spaced arms formed on said stem above said base, a shaft supported by said arms, means adjustably engaged with said shaft for adjusting said arms, a member rotatably supported on said shaft between said 30 arms and having the movement thereof controlled by the adjustment of said arms, and a pen socket supported on said rotatable member and adapted to be universally adjusted with respect to said base.

12. A pen supporting device comprising an internally threaded base sleeve, an upper 40 base member having a threaded shank adjustably engaged in said base sleeve, a spring controlled fork member rotatably engaged in said upper base member and including a pair of spaced apertured arms, an adjustable shaft unit supported by said apertured arms, a swivel member rotatably mounted on said 45 shaft between said arms, said shaft being adapted to be adjusted to control the frictional engagement of said arms with respect to said rotatable swivel member, and a pen socket removably engaged on said swivel 50 member and adapted to be moved with a universal movement with respect to said top base member.

13. A pen supporting device of the class described comprising a base member, a fork 55 unit rotatably supported therein, an adjustable barrel shaped unit supported on said fork unit and including a rotatable portion the movement of which is controlled by the forked member depending upon the adjustment of said barrel shaped unit, and a pen receiving socket removably engaged radially in said rotatable portion.

14. A pen supporting device comprising a 60 base member, a forked unit rotatably supported therein, a barrel shaped unit sup-

ported on said forked member and including adjustable interfitting end sections and a rotatable intermediate section, and a pen receiving socket removably engaged in said intermediate section and adapted to be adjusted with a universal movement with respect to said base member.

15. A pen supporting device of the class described comprising a base unit, a supporting member rotatably mounted therein, a 70 barrel shaped unit supported on said support, and a pen socket removably engaged with said barrel shaped unit, said barrel shaped unit comprising in combination a shaft section supported by and interfitting the support, a washer shaped to interfit said support to hold the washer against rotation, a swivel member rotatably engaged on said shaft section for receiving the socket member, and a headed screw section adjustably 75 engaged with said shaft section adapted to be adjusted to control the rotatable movement of said swivel member.

In testimony whereof I have hereunto subscribed my name at Chicago, Cook County, Illinois.
